[57] CLAIM

The ornamental design for a folding, refrigerated serving table, as shown and described.

DESCRIPTION

FIG. 1 is a side elevational view of a folding, refrigerated serving table according to the invention;

FIG. 2 is an end elevational view as seen along lines 2—2 of FIG. 1;

FIG. 3 is a top view as seen along lines 3—3 of FIG. 1;

FIG. 4 is a longitudinal sectional view taken along lines 4—4 of FIG. 3; and

FIG. 5 is a perspective view thereof.
